ONE-PIECE REINFORCED CARTON

Reynolds Guyer, St. Paul, Minn., assignor to Wal-dorf Paper Products Company, St. Paul, Minn., a corporation of Minnesota

Application July 12, 1946, Serial No. 683,111

2 Claims. (Cl. 229—37)

1

My invention relates to an improvement in one piece reinforced carton wherein it is desired to provide a carton possessing high stacking strength from a single sheet of carton stock.

Many cartons are at present being used for the packaging of materials such as cheese which is relatively heavy and yet which is somewhat compressible even in a solid state. After such cartons have been filled they are usually stacked on a movable platform and maintained on this platform until they are shipped. It has often been necessary to provide shelves or self-supporting trays on these platforms in order to prevent compression of the lower packages of the stack. The use of such shelves or trays requires considerable time for the operation which might be avoided if the packages possessed sufficient stacking strength to resist compression. As such packages often include two pounds of cheese, for example, there is considerable weight on the lowermost packages of the stack and the cartons must be extremely rigid to withstand this weight.

A feature of the present invention resides in the provision of a carton having side and end walls which are comprised of at least three thicknesses of carton stock. As a result relatively light paper board may be used in the formation of the cartons and a minimum of paper stock is required. The triple thickness side and end walls provide the necessary stacking strength while the top and bottom surfaces of the package are of single thickness stock. As a result a lesser amount of paper board is employed than would be necessary if the entire carton were formed of paper board sufficiently thick to withstand equal pressure.

A feature of the present invention resides in the provision of a carton having side walls of triple thickness stock, the three laminations being adhered together. I have found that the carton wall formed of three adhered laminations is usually stronger and will withstand more pressure than a single sheet of equal thickness.

A further feature of the present invention lies in the provision of a carton which can be formed on gluing apparatus in common use. My carton is so constructed that the folding operations can be conveniently accomplished on a gluer of the type usually found in carton manufacturing plants.

A further feature of the present invention resides in the provision of a carton which can be easily opened up to remove all of the contents in a body. Such a structure is of decided ad-

2

vantage for use with certain products such as cheese wherein it is desired to remove the entire loaf of cheese bodily from the carton so that it may be sliced or cut.

5 A feature of the present invention resides in the provision of a one piece carton in which two of the sides may be opened up so that the product contained is easily accessible. When my carton is opened two adjacent sides of the carton 10 may be folded open, revealing two sides of the brick of cheese or other material contained therein, thereby rendering the material readily accessible.

15 A further feature of the present invention resides in the provision of a carton which is of the reclosing type. My carton may be opened up and part of the contents removed. The contents can then be replaced in the carton and the carton closed to protect the remainder of 20 the contents.

25 A further feature of the present invention lies in the provision of a carton of the tubular type which can be shipped in flat condition and conveniently stored. At the same time my carton 30 may be sealed in the manner common to such tubular cartons without the provision of special sealing equipment.

35 An added feature of the present invention resides in the fact that the contents may be conveniently inserted in a transparent envelope or wrapper placed within the carton and formed so that the seam of the bag or wrapper is not exposed when the package is open. In the packaging of cheese for example, printed transparent wrappers are usually provided which have at least one longitudinal seam extending the length thereof. This bag may be conveniently inserted in the package so that the seam is on the bottom of the loaf when the carton is opened so that 40 the goods contained are effectively displayed.

45 An added feature of the present invention resides in the provision of a tubular carton which may be filled and sealed on usual apparatus employed for such cartons and yet which may open up along a longitudinal edge of the carton to display the entire contents.

50 These and other objects and novel features of my invention will be more clearly and fully set forth in the following specification and claims.

In the drawings forming a part of my specification:

55 Figure 1 is a diagrammatic view showing a carton blank embodying my new construction.

Figure 2 shows the carton blank of Figure 1 in partially folded condition.

Figure 3 is a sectional view of the carton blank, the position of the section being indicated by the line 3—3 of Figure 2.

Figure 4 is a perspective view of my carton when sealed in tubular form, a portion of the wall of the carton being broken away to show the construction thereof.

Figure 5 shows the end flaps of the carton in partially folded position. This view is diagrammatic to show the order in which the flaps are sealed as under usual practice one end would be entirely sealed before the other end was sealed.

Figure 6 is a perspective view of the sealed carton showing diagrammatically the manner in which the carton may be opened.

Figure 7 is a perspective view of the carton in open position.

Figure 8 is a transverse section through the sealed carton showing the arrangement of the side walls thereof.

The carton A is formed from the blank best illustrated in Figure 1 of the drawings. The blank A includes a reinforcing panel 10 hingedly connected by the score line 11 to the outer side wall panel 12. The panel 12 is foldably connected along the fold line 13 to the top panel 14. The top panel 14 is foldably connected along the fold line 15 to the outer side wall panel 16. This outer side wall panel is connected by a fold line 17 to the intermediate side wall reinforcing panel 19. The panel 19 is connected along the score line 20 to the inner side wall reinforcing panel 21. This panel 21 is connected along the fold line 22 to the bottom panel 23. The bottom panel 23 is foldably connected along the score line 24 to the inner side wall reinforcing panel 25. In the construction illustrated the various fold lines 11, 13, 15, 17, 20, 22, and 24 are substantially parallel.

At certain of the fold lines where the stock is doubled back upon itself it may be desirable to provide a cut score or a perforated line, particularly where the fold line is not visible on the exterior of the package. For example the paper stock is folded through 180° along the fold line 20 on the interior of the carton and this fold line is preferably perforated or formed as a cut score to simplify the folding operation.

The blank shown in Figure 1 of the drawings is folded into the condition illustrated in Figure 2 of the drawings. To accomplish this result the stock is folded along the score or perforated line 20 so that the panel 19 overlies the panel 21. Adhesive 26 is applied between the panels 19 and 21 to adhere these two panels together. In the construction shown the adhesive 26 is shown in two spaced strips extending lengthwise of the panels, but actually this adhesive may extend the whole width of the panels 19 and 21 if desired. Both of the panels 19 and 21 are folded beneath the panel 16, the folding taking place along the fold line 17. Adhesive 27, either in separate strips or in a wide band, is applied between the panels 16 and 19 to adhere these panels securely together. The order in which the panels are folded and glued may be reversed if desired, the panel 19 being folded beneath the panel 16 and adhered thereto prior to the time the panel 21 is folded against and adhered to the panel 19. Alternatively the two folding operations may take place simultaneously.

The foregoing folding operations provide a

triple thickness wall which will eventually form one side wall of the carton. The triple thickness wall is composed of the panels 16, 19, and 21 which appear in surface contacting relation at the left hand side of Figure 8. In this figure the panels are shown slightly spaced in order to indicate the adhesive therebetween. Actually, however, when adhered these panels will be in surface contacting relationship.

The panel 10 is likewise folded along the fold line 11 to underlie the panel 12. Adhesive 29 is applied between the panels 10 and 12 to adhere these two panels closely together. The adhesive 29 is shown in two spaced strips, but obviously the entire surface of these flaps may be adhered together if deemed advisable.

The blank when thus folded appears as illustrated in Figure 2 of the drawings and the manner in which the folding appears is also visible in Figure 3. The carton is now ready to be adhered in tubular relationship as indicated in Figure 4 of the drawings.

The carton is next folded either along the fold line 22 or the fold line 24 and the combined panels 10 and 12 are folded into surface contacting relationship therewith. If the panel 25 is folded along the fold line 22 the combined panels 10 and 12 are folded about the fold line 13 to overlie the panel 13 to overlie the panel 25. Similarly if the first folding operation takes place along the fold line 24, the panels 10 and 12 together with the panel 14 are folded along the fold line 15 to overlie the panel 25. Adhesive 30 is applied between the panels 10 and 25 to adhere these panels together.

As indicated in Figure 1 of the drawings I prefer to print a portion of the surface of the panels 10 and 25 with ink capable of repelling the adhesive employed. This printing is arranged to leave a rectangular relatively narrow strip of unprinted stock indicated by the broken line 31 enclosed within a larger printed area indicated by the broken line 32. Similarly the panel 10 includes a printed area bounded by the broken line 33 leaving a corresponding unprinted strip bounded by the broken line 34 near the fold line 11. The surfaces 31 and 34 correspond in folded condition of the blank so that glue applied either to the surface 31 or to the surface 34 will cause adherence between the surfaces 31 and 34. This procedure is followed in order to limit the tearing of the liner of the carton stock as the carton is opened, thus preventing strips or ribbons of carton stock liner from adhering to the panels 10 and 25 after the carton has been opened.

When the carton has been adhered as described, the carton is of tubular form illustrated in Figures 4 and 8 of the drawings. Each of two opposed walls of the carton are of triple thickness and the remaining opposed walls are of single thickness thus providing maximum stacking strength with a minimum of carton stock.

A closing flap 36 is foldably connected to one end of the panel 23 along a fold line 37. Cooperating closing flaps 39, 40, and 41, respectively, are connected to the panels 16, 14, and 12 along a common fold line 42. All of the flaps 36, 39, 40 and 41 are of substantially the area of the end of the carton although two of these flaps 40 and 41 may be somewhat smaller if desired. A closing flap 42 is connected to the panel 23 along a fold line 43 parallel to the fold line 37. Cooperable closing flaps 44, 45, and 46 are connected to the

panels 16, 14, and 12 along a fold line 47 substantially aligned with the fold line 43.

With the carton in the position illustrated in Figure 4 of the drawings one end of the carton is sealed to provide a closed carton end. To accomplish this result adhesive is applied to one of the flaps such as to the flap 49. The flap 42 is then folded to overlie the end of the carton and the flap 49 is folded over the flap 42 and adhered thereto. Adhesive is next applied to one of the remaining carton flaps such as the flap 45. The flap 46 is then folded over the previously folded flaps 42 and 44 and the flap 45 is folded thereover and adhered thereto. As a result two pairs of flaps are provided at the lower end of the carton and the flaps of each pair are individually connected together by the two pairs of flaps remaining unadhered.

After the carton has been filled a similar sealing process may be used to seal the upper end of the carton. The flaps 36 and 39 are first folded into superimposed relation and adhered together and the flaps 40 and 41 are next folded into superimposed relation over the flaps 36 and 39 and the flaps 40 and 41 are adhered together.

When sealed the carton appears as illustrated in Figure 6 of the drawings. Panel 14 usually forms the top panel and panel 23 usually forms the bottom panel. The side walls which are of triple thickness and the end walls which are of four thicknesses of paper stock form a rigid support so that the carton possesses high stacking strength. When it is desired to open the carton an instrument such as a knife blade B is inserted between the folded edge 11 connecting panels 10 and 12 and the fold line 24 connecting panel 25 to the bottom panel 23. The knife blade severs the relatively narrow line of adhesive 30, permitting the top panel together with the adhered panels 10 and 12 to fold upwardly from the remainder of the carton along the fold line 15 as indicated in Figure 7 of the drawings. The top panel is connected to the front panel 12 by means of flaps 40 and 41 at one end of the carton and by means of flaps 45 and 46 at the other end of the carton, thus holding the top and front side wall of the carton in right angular relationship as illustrated. As soon as the top of the carton is folded upwardly as described the inner front reinforcing panel 25 is free to fold downwardly along the fold line 24 so as to expose two sides of the contents of the carton. The bottom panel 23 and the triple thickness side wall comprising panels 16, 19 and 21 are held in right angular relation by the flaps 36 and 39 at one end of the carton and by the flaps 42 and 44 at the other end of the carton.

If desired a part of the contents of the carton may be removed and the remainder replaced to rest upon the bottom panel 23. The panel 25 may then be folded up into vertical position and the top closure structure including panels 14, 10 and 12 may then be hinged down into the position shown in Figure 6 of the drawings to enclose the carton contents.

In accordance with the patent statutes, I have described the principles of construction and operation of my carton, and while I have endeavored to set forth the best embodiment thereof, I desire to have it understood that obvious changes may be made within the scope of the following claims without departing from the spirit of my invention.

I claim:

1. A carton comprising two foldably connected sections, one section including a bottom panel and a rear wall panel, and the other section including a top panel and a front wall panel, end flaps at each end of said panels, the end flaps at each end of the bottom wall panel being arranged in overlapping surface contact with the corresponding end flaps of the rear wall panel, the end flaps of said top panel being arranged in overlapping surface contact with the corresponding end flaps of the front wall panel, means securing the overlapping end flaps of each section together to hold the bottom panel and rear wall panel in substantially right angular relationship and to hold said top panel and said front wall panel in substantially right angular relationship, and a free panel hingedly connected to the forward edge of said bottom panel and foldable from vertical position to horizontal position in substantially the plane of the bottom panel, a fold line connecting the upper edge of said rear wall panel and the rear edge of said top panel to hingedly connect said sections, the two sections being foldable from a closed position in which the overlapping end flaps of the bottom panel and rear wall panel lie inwardly of the end flaps connecting the top panel and the front wall panel, and said free panel lies inwardly of the front wall panel to an open position in which the end flaps of one section do not overlap the end flaps of the other section and in which the free panel is folded substantially into the plane of the bottom panel.
2. The structure described in claim 1 and including an adhesive connection between said front wall panel and said free panel in closed position of the section.

REYNOLDS GUYER.
